RAIL BRACE

George Arnold, Shaker Heights, Harry A. Schultz, Garfield Heights, and Edwin E. Rhoads, Solon, Ohio, assignors to Cleveland Frog & Crossing Co., Cleveland, Ohio, a corporation of Ohio

Application July 28, 1948, Serial No. 41,085

3 Claims. (Cl. 238—292)

1

This invention relates to a rail brace such as is applied to a railroad rail to resist any tendency of the rail to overturn outwardly from the center of the track and to clamp it to the tie plate or base plate (or switch plate) on which it rests, thus holding the rail against movements relative to the plate, which latter in turn is secured to a supporting tie as is well understood in the art.

Rail braces of the type contemplated by this invention are most frequently applied against the stock rails alongside split switch points, but their use is not necessarily limited to such application.

Further, braces of this type are frequently made adjustable, to compensate for variations in the dimensions of the rail, the seat for the rail and brace, in the brace itself, and also to afford a means of re-tightening the assembly after wear takes place.

Rail braces employed for this purpose generally have a portion which engages one of the sloping base flanges of the rail and the vertical web of the rail where it merges with the base flanges and a portion which engages the web beneath the rail head. Heretofore the rail braces have been secured to the base plates in rail clamping and bracing position by vertical hold-down or clamping bolts extending through the base plates and braces. Difficulty has been experienced with the rail braces in use in that the braces tend when in track to work downwardly of the sloping base flange of the rails and away from the web of the rails until the braces do not effectively clamp the rails to the base plates or brace the rails against tilting or moving away from the shoulder of the base plates.

Various arrangements have been employed to overcome this tendency of the rail braces to work away from the rails as, for instance, it has been usual to employ wedge members inserted between the rail braces and fixed abutments or back stops secured to the base plates, the function of the wedges being to force the braces toward the rails.

An object of the present invention is to provide a rail brace which is so constructed and is so secured to the base plate when installed it tends at all times and under trackage conditions to work toward the rail rather than away from the rail, thus insuring the maintenance of the necessary clamping and bracing relationship between the brace and the rail.

Another object is to provide a rail brace which is so constructed and is so secured to the base

2

plate in rail engaging position that it will maintain such position automatically without the necessity of employing wedges or similar arrangements for the purpose of taking up looseness between the brace and the rail.

A further object is to provide a rail brace which is so constructed and is so secured to the base plate as to maintain itself under operating conditions in tight clamping and bracing relationship with the rail.

A further object is to provide a rail brace of improved efficiency as compared to the braces now in use and which brace when installed and in use maintains at all times its proper tight engagement with the rail and exerts on the rail the proper and desired lateral and downward bracing and clamping forces without tendency of tipping the rail.

More specifically, an object of the invention is to provide a rail brace as specified in the foregoing objects and wherein the hold-down bolts of the brace are disposed vertically to the base plate.

Further and additional objects and advantages will become apparent hereinafter during the detailed description of an embodiment of the invention which is to follow.

The invention contemplates constructing a rail brace and securing the same in rail clamping and bracing position in a manner such that the force exerted by the vertical hold-down bolts of the brace produces on the brace, in addition to a vertical or hold-down force, a component force tending to move the brace toward the rail and causing that portion of the brace which engages with one of the sloping base flanges of the rail to move upwardly of said base flange into tight engagement with the rail, as distinguished from the prior rail brace constructions wherein there is a tendency for the rail braces to move downwardly of the sloping base flange of the rails and work loose from proper and effective rail clamping and bracing position.

Referring to the accompanying drawing illustrating an embodiment of the invention,

Fig. 1 is a transverse vertical section through a railway rail, base plate and brace, and

Fig. 2 is a horizontal sectional view taken substantially on line 2—2 of Fig. 1, looking in the direction of the arrows.

The rail shown in the drawings is of usual construction and comprises the base flanges 11 having downwardly sloping upper surfaces 12. The base flanges are integral with the vertical web 13 of the rail and the downwardly sloping

surfaces 12 merge at their upper ends into the outer surfaces of the web by curved surface portions. The web 13 at its upper end is integral with the rail head 14, the underside of the rail head and the outer surfaces of the web merging by curved surfaces. The base plate 15 which is secured to the top of a cross tie is provided on its upper side with a recess into which fits the base flanges of the rail. The base plate 15 to the right of said recess as viewed in the drawings is provided with abutment means in the form of a transverse slot 16 for a purpose later to be explained.

The rail brace comprises a block B which preferably is an integral casting or forging and said block includes a vertically extending portion 17 provided at its upper end with a rail web engaging portion 18. The block B also is provided with a downwardly inclined portion 19 connected to the vertical portion 17 by an intermediate portion 20, having either a convex or flat surface which engages the downwardly sloping surface 12 of one of the base flanges of the rail and adjacent the web when the brace is installed, i. e., the right hand base flange as viewed in the drawing.

It will be noted that when the rail brace is installed there is a clearance C between the web engaging portion 18 at the upper end of the vertical portion 17 and the underside of the rail head, wherefore the brace in use exerts no upward force on the underside of the rail head tending to tip the rail; that is, the portion 18 exerts only a horizontal bracing force against the web of the rail. It will also be noted that a clearance C¹ exists between the vertical portion 17 of the block and the web of the rail.

The downwardly inclined portion 19 of the block is provided with spaced openings 21 elongated in a direction longitudinally of the base plate and extending toward the rail. The block B outwardly and to the right of the inclined portion 19 is provided with a foot portion 22 which when the block is installed is substantially horizontal and bears upon the upper side of the base plate. It will be noted that there is a clearance between the upper side of the base plate and the inclined portion 19 of the block. The block B is provided with integral downwardly curved side walls 23 and 24 uniting the portions 17, 18, 19, 20 and 22.

The base plate 15 is provided with vertical openings underlying the openings 21 and bolts 25 are mounted in said openings in the base plate with the heads of the bolts countersunk in the lower ends of the openings. The bolts 25 extend perpendicularly from the base plate through the openings 21 and a substantial distance above the portion 19 of the block and are threaded at their upper ends.

A combined washer and holding member 26 is used in conjunction with the block B and said member 26 has at its right hand end as viewed in the drawing a downwardly curved portion 27 which engages in the abutment means formed by the transverse slot 16 of the base plate. The opposite end of the member 26 is provided with an elongated boss 28, the undersurface 29 of which is downwardly inclined so as to lie flat against the downwardly inclined upper surface of the portion 19 of the block. The upper surface 30 of the elongated boss 28 is substantially horizontal. The boss 28 is provided with spaced openings 31 overlying the openings 21 in the block B and the bolts 25 extend vertically through

the spaced openings 31 as clearly indicated in Fig. 1. The openings 31 are formed with a downward slightly divergent taper, and it will be noted that the bolts 25 have a relatively close fit in the upper ends of the openings 31. The member 26 between the portion 27 and the boss 28 is downwardly inclined and is spaced from the block.

When a rail is mounted in the recess on the upper side of the base plate 15 and the block B is positioned as indicated in Fig. 1 with the bolts 25 extending vertically through the openings 21, then the member 26 is positioned on the block with the bolts extending through the openings 15 31 and with the inclined surface 29 of the boss 28 of the member 26 engaging the upper surface of the inclined portion 19 of the block. Also at this time the downwardly curved portion 27 of the member 26 is positioned in the slot 16 of the base plate. Heavy spring washers or coil springs 32 are positioned on the bolts 25 and engage the horizontal surface 30 of the boss 28 of the member 26. Then cap nuts 33 are screwed downwardly on the bolts to firmly press the washers or other springs 32 into engagement with the surface 30 and thus to apply the required hold-down bracing forces to the braces.

It will be observed, although the bolts 25 are perpendicular, the force exerted by the nuts and washers carried by the bolts on the block B and member 26 produces because of the inclined upper surface of the portion 19 of the block and the inclined lower surface 29 of the boss 28 resultant lateral forces in addition to the vertical hold-down forces. It will be observed that boss surface 29 and the upper surface of the portion 19 are substantially parallel to the surface 12 of the one rail base flange. These resultant lateral forces function to urge the block B toward the rail with the engaging side of the intermediate portion 20 of the block riding upwardly of the downwardly sloping surface 12 of the right hand base flange of the rail. Also these resultant forces act to urge the member 26 toward the right as viewed in the drawing to tightly engage the portion 27 of the member 26 with the right hand side of the slot 16 in the base plate 15. In other words, the hold-down forces tend to and actually do function to urge the block B toward the left and toward the rail and the member 26 toward the right and the portion 27 thereof into tight contact with the right hand side of the slot 16. Consequently the rail brace when installed in track will maintain itself in the proper tight engagement with the rail and will have no tendency for the portion 20 to work downwardly of said surface 12 of the rail base flange under vibration or other causes as is frequently the case with present day rail braces. Therefore the rail brace will maintain itself automatically at all times in the proper relationship to the rail to effectively and safely hold the latter against movement relative to the base plate 15.

Although a preferred embodiment of the invention has been illustrated and described herein it will be understood that the invention is susceptible of various modifications and adaptations within the scope of the appended claims.

Having thus described our invention, we claim:

70 1. A rail brace and supporting means of the type specified and comprising, in combination, a base plate provided on its upper side with a recess adapted to receive and support the base flanges of a rail, said base plate being provided with upwardly extending perpendicular bolts and with

an abutment means on its upper side, a block having a portion adapted to engage the rail web beneath the head thereof and an intermediate portion adapted to engage the downwardly sloping upper surface of one of the base flanges of the rail adjacent the web thereof, said block also being provided with a downwardly inclined portion integral with and extending from said intermediate portion and having its underside spaced from the downwardly sloping upper surface of said one base flange of the rail and from the upper surface of the base plate, said inclined portion being provided with openings elongated in the longitudinal direction of the base plate and through which said bolts extend, said block also being provided with a foot portion integrally connected with said inclined portion and extending substantially horizontally therefrom and having surface contact with the upper side of the base plate, a washer member operatively associated with said block and provided with boss means having openings therein through which said bolts project, said boss means having a substantially horizontal upper surface and a downwardly inclined under surface contacting the upper side of the inclined portion of the block, said washer member having a portion extending from the boss means thereof and overlying said foot portion of the block and provided at its outer end with an abutment engaging portion, spring means on said bolts engaging the substantially horizontal upper surface of said boss means, and hold-down nuts on said bolts engaging said spring means.

2. A rail brace and supporting means of the type specified and comprising, in combination, a base plate provided on its upper side with a recess adapted to receive and support the base flanges of a rail, said base plate being provided with upwardly extending perpendicular bolts and with an abutment means on its upper side, a block having a portion adapted to engage the rail web beneath the head thereof and an intermediate portion adapted to engage the downwardly sloping upper surface of one of the base flanges of the rail adjacent the web thereof, said intermediate portion being of arcuate configuration and having its convex side in engagement with said one base flange, said block also being

provided with a downwardly inclined portion integral with and extending from said intermediate portion and having its underside spaced from the downwardly sloping upper surface of said one base flange of the rail and from the upper surface of the base plate, said inclined portion being provided with openings elongated in the longitudinal direction of the base plate and through which said bolts extend, said block also being provided with a foot portion integrally connected with said inclined portion and extending substantially horizontally therefrom and having surface contact with the upper side of the base plate, a washer member operatively associated with said block and provided with boss means having openings therein through which said bolts project, said boss means having a substantially horizontal upper surface and a downwardly inclined under surface contacting the upper side of the inclined portion of the block, said washer member having a portion extending from the boss means thereof and overlying said foot portion of the block and provided at its outer end with an abutment engaging portion, spring means on said bolts engaging the substantially horizontal upper surface of said boss means, and hold-down nuts on said bolts engaging said spring means.

3. A rail brace and supporting means as defined in claim 2 and wherein the abutment means on the upper side of the base plate is in the form of a groove extending transversely of the plate while said washer member has a portion extending from the boss means thereof and overlying in spaced relation said foot portion of the block and provided at its outer end with a downwardly turned flange engaging in said groove.
